UNITED STATES PATENT OFFICE.

JESSE A. CRANDALL, OF BROOKLYN, NEW YORK.

TOY GUN.

SPECIFICATION forming part of Letters Patent No. 267,679, dated November 21, 1882.

Application filed June 29, 1882. (No model.)

To all whom it may concern:

Be it known that I, JESSE A. CRANDALL, of Brooklyn, in the county of Kings and State of New York, have invented an Improved Toy Gun, of which the following is a specification.

Figure 1 is a longitudinal central section of my improved toy gun. Fig. 2 is a side view, partly in section, of the same; Fig. 3, a top view thereof; and Fig. 4, a cross-section on the line *c c*, Fig. 3.

This invention relates to a new toy gun, which is calculated to throw a ball or other implement with considerable precision and quite a distance; and the invention consists in the combination of parts hereinafter more fully described.

In the accompanying drawings, the letter *A* represents the stock of my improved toy gun, which stock may be in the form of the stock 20 of a rifle, and which connects with the rear end of a long stick, *B*, that takes the place, so far as appearances go, of the rifle-barrel. In the front portion of the stock *A* is hung a trigger, *C*, which is held in the catching position by a rubber cushion, *a*, placed behind it into a recess formed in the stock for its reception.

D is a rod, of metal or the like, secured upon the stick *B* in such manner as to connect therewith or with the stock *A* behind the trigger, as at *b*, and with the stick *B* at the outer end of said rod *D*, as at *d*. The rod *D* is the guide for the ball-propeller *E*, which is a slide mounted on said rod, adapted to be moved along the same from one end to the other. The slide 35 or ball propeller *E* connects by two rubber straps, *F* *F*, with the ends of a cross-bar, *e*, that is fixed to the front of the stick *B*. The rear ends of the straps *F* connect with the ends of the slide *E*, as is clearly shown in Fig. 3.

Behind the front end, *d*, of the rod *D* is placed a cushion, *g*, of india-rubber or other suitable material.

The gun operates as follows: When the straps are slack, as in Fig. 2, the operator takes hold of the slide *E* and pulls it back toward the trigger until the said slide arrives near the back end of the rod *D* and has its lower edge engaged by the shoulder of the trigger, as shown in Fig. 1. The ball *h* to be 45 propelled is then placed against the front face of the slide *E*. The said slide *E* has a form resembling the counter of a boot or shoe, so as to form a receptacle open in front, in which

the ball *h* can be readily received, and in which, while being propelled forward, it will be prevented from flying out sidewise. Aim being taken, the trigger is pulled and the slide is at once violently thrown forward by the straps *F*, carrying the ball with it and causing it to fly in the desired direction to the extent of the 55 force given out by the straps. The slide *E* is finally arrested by the cushion *g*.

It will be perceived that this gun is of very simple construction, can readily be kept in repair by a boy, and will be a source of great 60 amusement. It may even be usefully employed for hunting cats on back-yard fences, or for analogous purposes.

Considerable importance is attached to the shoe-like structure of the slide *E*, which, as 70 already stated, guides the ball or object to be thrown in a longitudinal direction, preventing it flying off sidewise.

The success of the toy gun depends also upon the use of the rod *D*, or equivalent rib on the stick, which guides the shoe-like slide in its 75 forward motion, and insures, therefore, greater success in hitting an object. If the rod *D* is of sufficient strength, the stick *B* can be dispensed with.

The shoe-like structure of the slide *E* is clearly shown in Fig. 3, where the said slide is represented as being partly composed of a lower cross-piece, *i*, which receives the rear ends of the straps *F*, and upon which the shoe-like 80 body *E* is fastened.

In lieu of the straps, springs may be employed. Two rods *D* may be used on one stock *A* in lieu of one, in which case but a single propelling strap or spring may be employed 90 for moving the slide.

I claim—

The combination of the stock *A* and stick *B* with the rod *D*, secured in said stock and in said stick, and with the cross-piece *e*, straps 95 *F*, ball-carrying slide *E*, cushion *g* on rod *D*, trigger *C*, and trigger-spring, said cross-piece *e* being at the front of stick *B* and said trigger beneath the rod *D*, the slide *E* being adapted to carry the projectile above said rod *D*, substantially as specified.

JESSE A. CRANDALL.
